DESIGN FOR A LENS STRAP

Harwood S. Taylor, Rochester, N. Y., assignor to
Shuron Optical Company, Inc., Geneva, N. Y.,
a corporation of New York

Application October 9, 1937, Serial No. 72,094

Term of patent 14 years

To all whom it may concern:

Be it known that I, Harwood S. Taylor, a citizen of the United States of America, residing at Rochester, New York, have invented a new, original, and ornamental Design for a Lens Strap, of which the following is a specification, reference being had to the accompanying drawing forming part thereof, in which:

Figure 1 is a front elevation of the lens strap showing my new design.

Figure 2 is a side elevation thereof.

The dominating features of the design reside in the parts shown in full lines in the figures of the drawing.

I claim:

The ornamental design for a lens strap, as shown and described.

HARWOOD S. TAYLOR.
